UNITED STATES PATENT OFFICE.

MANUEL A. T. GILLBEE, OF PHILADELPHIA, PENNSYLVANIA.

DESIGN FOR AN ARTICLE OF MANUFACTURE.

56,808.

Specification for Design.

Patented Dec. 28, 1920.

Application filed August 15, 1919. Serial No. 317,816. Term of patent 3½ years.

To all whom it may concern:

Be it known that I, MANUEL A. T. GILLBEE, a citizen of the United States, residing in Philadelphia, Pennsylvania, have invented a certain new, original, and ornamental Design for an Article of Manufacture, of which the following is a specification, reference being had to the accompanying drawing forming part thereof, in which:

The figure is a face view of a card mount showing my new design.

I also contemplate using this design in the form of book and booklet covers, picture frames, portfolios and similar articles of manufacture wherein the design may be applied by any printing or embossing operation common among the arts.

I claim:

The ornamental design for an article of manufacture substantially as shown.

M. A. T. GILLBEE.
